UNITED STATES PATENT OFFICE.

VINCENT N. VOGT, OF DANSVILLE, NEW YORK.

SHOE-SHINING MACHINE.

1,330,665.

Specification of Letters Patent. Patented Feb. 10, 1920.

Application filed February 25, 1919. Serial No. 279,040.

To all whom it may concern:

Be it known that I, VINCENT N. VOGT, a citizen of the United States, residing at Dansville, in the county of Livingston and 5 State of New York, have invented new and useful Improvements in Shoe-Shining Machines, of which the following is a specification.

This invention has reference to an improved shoe shining machine.

An object of the invention is to produce an apparatus of this character which will be automatic in action and which will apply the blacking and polish the shoes in an 15 expeditious and highly satisfactory manner.

A further object of the invention is to produce a shoe shining apparatus which shall be of a simple construction so that the same may be cheaply manufactured and 20 marketed, and one which will perform the functions for which it is devised with ease, accuracy and certainty.

Many other objects and advantages will 25 present themselves as the nature of the construction is better understood, reference being had to the accompanying drawings in which there is illustrated a simple and satisfactory embodiment of the improvement, the 30 nature of the same being such, however, as to render the same necessarily susceptible to various changes and modifications, all of which however, falling within the scope of what is claimed.

In the drawings:

35 Figure 1 is a top plan view of a shoe shining apparatus constructed in accordance with this invention.

Fig. 2 is a sectional view approximately on the line 2—2 of Fig. 1.

40 Fig. 3 is a sectional view approximately on the line 3—3 of Fig. 1.

Fig. 4 is a sectional view approximately on the line 4—4 of Fig. 2.

45 Fig. 5 is a detail transverse sectional view showing the arrangement of parts when the polishing brush is in operative position.

Fig. 6 is a similar view showing the arrangement of parts when the blacking applying brush is in operative position.

50 Fig. 7 is a detail longitudinal sectional view approximately on the line 7—7 of Fig. 1.

Fig. 8 is a detail sectional view approximately on the line 8—8 of Fig. 1.

Fig. 9 is a detail sectional view approximately on the line 9—9 of Fig. 1.

Fig. 10 is a plan view of the feed for the blacking or polish applying brushes.

Fig. 11 is a sectional view approximately on the line 11—11 of Fig. 10.

Fig. 12 is a sectional view approximately on the line 12—12 of Fig. 10.

The frame for the improvement may be suitably incased so that the operative elements or mechanism carried thereby may be 65 inclosed and protected. The frame 15 may rest upon the usual platform of a boot-blacker's stand, the said frame being of a height approximately equaling that of the ordinary foot rests on such stands.

The device is primarily designed to be operated by suitable motor power, as will hereinafter be set forth in detail, but, if desired, the device may be hand operated, in which event the crank shaft, as illustrated 70 by the dotted lines in Fig. 1 of the drawings may have one of its ends formed with a crank handle, the same being indicated by the numeral 16. The frame is in the nature a square or oblong structure suitably proportioned and near the center thereof is secured on the base 17 therefor an upstanding block 18 having a reduced round extension 19 forming a pivot or shaft for a comparatively large flat wheel 20. The wheel, upon 75 its upper face is peripherally formed with teeth 21, and on two of its oppositely disposed spokes 22, with cam members. Two cam members 23 and 24 are provided upon 80 each of the referred to spokes 22, the said 85 cams being arranged concentric with the toothed frame of the wheel.

Meshing with the teeth 21 of the wheel 20 is a pinion 25, the same being carried by a shaft 26 mounted in suitable bearings 27, 95 and having a chain and sprocket connection with the drive shaft of a motor 28. The motor 28 is preferably electrically driven and is controlled by a switch comprising a stationary arm 29 and a spring movable 100 arm 30. This last mentioned arm or contact member is of a greater length than the arm or contact member 29, and the said arm 30 has on its end a lug 31 that is designed to

be received in a notch 32 in the under and smooth face of the rim of the wheel 20. The contact member or arm 30, it will thus be noted, serves as a stop for the wheel 20, 5 and being, as stated, of a spring nature is normally out of engagement with the contact 29 so that the circuit between the switch arms or contact members is normally broken. The contact member or arm 30 is disposed 10 directly below a coin chute 33. This coin chute is suitably supported on the frame 15, and a coin deposited therein and gravitating therethrough will, by the weight thereof, move the arm 30 out of engagement with the wheel 20 and into contact with the member 29, thus permitting electricity to flow 15 through the motor to operate the same, and consequently revolve the shaft 26 which, through the medium of its pinion 25 will likewise revolve the wheel 20.

The wheel 20 has formed on its rim at a suitable point, approximately centrally between the oppositely disposed pairs of cam members 23 and 24 an outstanding lug 25 which is in the nature of a cam wiper member and which is designated by the numeral 34. The main purpose of this member 34 will hereinafter be entered into. On the lug 34 is an upstanding lug 35 that is disposed in the path of contact with an arm 36 which is secured to a gate 37 that closes an opening in the lower side of the chute 33. Below the chute is a coin receiving receptacle 38. The gate 37 may have its inner face provided with offset fingers that contact with one of the sides of the coin received in the chute, so that when the lug 35 contacts with the arm 36 the gate will be swung to its open position, causing the 30 coin engaged thereby to be moved to one side of the contact member or arm 30 of the switch for the motor and to be deposited in the receptacle 38. Immediately after the arm 30 is relieved of the weight of the coin 35 the said arm, by the inherent resiliency thereof will be brought against the under face of the wheel 20 and the lug 31 on the said arm will be again received in the notch 32 to hold the wheel against further movement, and, of course, breaking the contact 40 halt the motor. It is, of course, not absolutely necessary to provide the gate 37 with the fingers as described, as the chute 33 may be so arranged as to permit of the coin 45 dropping off of the arm 30 when the gate 37 is opened.

The frame 15 at the front and near the top thereof has secured thereto a transversely arranged horizontally disposed plate 60 38'. On this plate, at suitable spaced intervals are secured upstanding brackets 39. These brackets are arranged in spaced pairs, and between each pair of the said brackets are pivotally secured widened head portions 65 40 of arms 41. On the outer or free end

of each of the arms 41 is a plate 42 having the rear portion thereof stepped or depressed as at 43. The plates 42 are shaped to correspond with the feet of the persons having their shoes shined, the heel portion 70 of the shoes resting on the depressed portion 43, and for the sake of convenience the plates and pivoted arms therefor will hereinafter be referred to as foot rests. Each of the foot rests has upon the under face 75 of the plates 42 thereof a depending member in the nature of a rod or arm which is indicated by the numeral 44. The free end of each of the arms 44 is preferably bifurcated and in the said bifurcation is received 80 a roller 45 which is pivoted thereto. These rollers are disposed in the path of contact with the pairs of cam members 23 and 24 carried by the wheel 20, and when the said rollers ride on the upper surfaces of the 85 cams the foot rests will be elevated. The arms 41 of the foot rests are provided with lugs 46 which contact with the brackets 39 limiting the swinging of the said foot rests in a downward direction. 90

At the opposite sides of each of the foot rests pans 47 are secured to suitable supports on the frame, the said pans being disposed a considerable distance below the foot rests, having their upper and open portions 95 arranged approximately flush with the upper face of the plate 38. These pans 47 are designed to receive therein the blacking or polish to be applied to the shoes that are operated on. Each of the pans receives 100 therein the block members 48 which are substantially rectangular in plan and which have their upper faces curved, so that the upper faces of the said blocks are convexed in side elevation. These blocks 48 are provided with rows of spaced openings 49 therethrough and between the said openings the said blocks, upon the upper faces thereof have cup-shaped depressions 50. Each pair of blocks is connected by a substantially U-shaped yoke 51, the yokes having their side members or arms pivotally connected to the blocks as at 52. The inner face of each pair of blocks has spaced lugs or pins 53 thereon disposed to the opposite 110 sides of the arms of the yokes 51 designed to contact with the edges of the said arms to limit the swinging of the said blocks. The yokes of the respective pairs of blocks are connected to the plates 42 of the respective foot rests, and it will be apparent that when the foot rests are in their normal depressed position the blocks 48 will be fully received in the pans 47, as illustrated in Fig. 3 of the drawings, and that when the rollers 115 45 ride over the cams 23 and 24 of the wheel 20 the said blocks will be elevated with the foot rests. These blocks 48 provide the feed means for applying the liquid blacking or polish to the blacking brushes, 120 130

as will hereinafter be more apparent. A downward movement of the blocks in the pans 47 permits of the liquid blacking or polish flowing through the openings 49 therein and a certain and determined quantity of the said liquid being received in the cup-like depressions or pockets 50, and it is only this quantity of the liquid that is received by the blacking brushes.

5 10 Journaled in suitable bearings 54 is a shaft 55. This shaft has reversely arranged pairs of cranks 56 and 57 respectively. The shaft has on one of its ends a sprocket wheel 116 around which is trained a sprocket chain 117. The chain is also trained around a sprocket wheel 118 that is keyed on the shaft 26, and it will be thus apparent that when the motor is in operation the shaft 55 will be revolved. Connected to each of 15 the cranks is a pitman 58. Each of the pitmen 58 is pivotally connected between upstanding ears 59 on a slide 60. Each of the slides is movable through suitable flanged guides 61 that are secured, as at 62 to the plate 38'. Each of the slides 60 has its outer end offset upwardly and pivotally connected, as at 63 to one of the end plates 64 of angle frames 65. The second or inner end plate 66 of each of the angle frames is formed 20 with an outstanding centrally arranged sleeve 67 that receives therein a rod which is in the nature of a shaft and which is designated by the numeral 68, the said shafts being rigidly supported on the rear of the 25 frame 15.

Two of the angle frames 65 disposed to one side of each of the foot rests have rigidly secured thereon a blacking applying brush 69 and a polishing brush 70, but the blacking and polishing brushes of the frames upon the opposite sides of the foot rests are adjustably mounted on such frames, the purpose for which and the construction of which will presently be described.

45 On each of the sleeves 67, at the outer end thereof is an upstanding arm or bracket 71, each having an opening therein through which passes a rod 72. The rods 50 72 have their free ends secured to upstanding arms 73 provided, upon their lower ends with enlargements in the nature of eyes 74 that are received on the respective shafts 68. The arms 73 are held against 55 turning on the shafts 68 in one direction by engagement with stops 75, carried by the said shafts 68, and the said arms are retained in engagement with the said stops through the medium of springs 76 contact- 60 ing therewith, the said springs being arranged in bores 77 formed in the upper and curved ends 78 of supporting brackets 79 secured, as at 80 to suitable plates 81 on the frame 15. The curved outer or upper 65 ends of the brackets 79 have their opposite

sides slotted in a line concentric with the curvature of the said ends of the brackets, the said slots being indicated by the numerals 82 and receiving therethrough the respective rods 72.

70 Pairs of alternating rods 72 are connected by links 83 and 84 respectively. These links have their ends provided with eyes through which the rods pass.

The outer or end rods 72 have secured thereto flexible elements 85 and 86 respectively. These flexible elements or cables are trained around groove or sheave wheels 87 and 88 respectively secured on the opposite sides of the frame 15, the said flexible 80 elements or cables having their free ends secured to the opposite sides, and adjacent the opposite ends of a centrally pivoted trigger 89. The trigger is in the nature of a substantially rectangular block 85 or plate and has one of its corners cut at an inclination as indicated by the numeral 90, and this angle corner is in the path of contact with the wiper member 34 on the toothed wheel 20. The wiper 90 member, as previously stated, is arranged on the wheel 20 approximately centrally between the oppositely disposed pairs of cam members 23 and 24, and it will be obvious that when the wheel is revolved 95 and the member 34 engages with the trigger 89, the said trigger will be swung upon its pivot, drawing on the flexible elements 86 connected to the outer rods 72, which rods, through the medium of the links 84 100 being connected to the central intermediate rods 72 will turn the said rods. This turning movement, or rather the swinging of the outer rods 72 against the pressure of the springs 78 in the bracket members 79 105 will turn the brush frames approximately one-half a revolution, bringing the blacking or polishing applying brushes to a position to apply the blacking or polish to the shoes which rest on the foot rests. 110

The turning of the rods, as above described, brings the polishing brushes to a substantially vertical position, or to a position as illustrated in Fig. 6 of the drawings, so that the said polishing brushes are out of contact- 115 ing engagement with the shoes to be operated on. Before the rods are turned to bring the polishing brushes to such position the rollers on the depending arms 44 of the foot rests ride over the cams 23 on the toothed wheel 20, elevating the foot rests and bringing the feed blocks 48 against the said brushes which, by the reciprocating movement imparted thereto by the crank shaft 55 and the connecting means between the said shaft and the frames of the brushes are treated to a desired quantity of the liquid blacking or polish to be applied to the shoes. When the blacking has been applied the rollers 45 ride off of the cams 23 and are 120 125 130

positioned between the said cams 23 and the cams 24. The rollers now ride on the cams 24 which elevate or swing the foot rests at an upward inclination. When in this position the wiper member 34 will have passed the trigger 89, so that the springs in the supporting brackets for the rods will return the said rods to their initial position, revolving the brush carrying frames on the shafts 68, 10 and bringing the polishing brushes to polishing position. It is to be understood that the brushes are reciprocated throughout the operation of the wheel 20, the sleeves 67 being of such a length so that the shafts 68 are at 15 all times received therein.

On the rear of the frame 15 is arranged a shaft 91 that is journaled in suitable bearings 92. This frame has at one of its ends a sprocket wheel 93 around which is trained a 20 twisted chain 94, the said chain being also trained around a sprocket wheel 95 on one end of the shaft 55. The shaft 91 has secured thereon vanes or blades received in suitable casings 96, the shafts 91, of course, 25 passing through bearing openings in the sides of the said casings. Each of these casings is provided with a spout 97, the mouth of the said spout being disposed a suitable distance from the free ends of the foot rests, 30 between the brushes that are disposed to the opposite sides of the said foot rests. By this arrangement it will be seen that a constant blast of air is delivered to the shoes on the foot rests so that the liquid blacking 35 applied thereto will be quickly dried and the polishing brushes can properly operate on the shoes to impart a polish thereto. The brushes on the frame to one side of each of the foot rests are rigidly secured thereto, 40 but the coöperating brushes, upon the opposite frames are adjustably associated with the said frames. This is necessary in order that shoes of different widths may be properly polished. The last mentioned frames 45 have their angle sides provided with spaced openings through which pass substantially U-shaped yokes 98, the ends of the said yokes being secured to the respective blacking applying brush and the polishing brush. 50 These yokes are each pivotally connected to links, indicated by the numerals 99 and 100 respectively. The link 100 is shorter than the link 99 and is pivoted to the said link 99. The link 99 has one end received in a 55 longitudinal slot 101 in a bearing member or arm 102. The end of the link 99 is provided with a laterally extending pin 103 that passes through elongated slots 104 in the sides of the member 102. In the slot 101 is a 60 spring 105, the said spring exerting a pressure between the inner wall of the slot and the end of the link, normally forcing the said link outward of the said slot. The member 102 has its inner end provided with 65 a head 106 preferably formed by flanging

the said member upon its upper and lower faces. This substantially T-shaped head is received in a groove 107 provided in a guide 108, the member 102 passing through a central opening in the said guide. The guides 70 are provided with depending members 109 having their ends provided with a connecting member 110, the latter being received in suitable bearings 111 carried by a portion of the frame 15. To the outer depending member 109 is pivotally connected a link 112. This link is in turn pivotally connected to a lever 113, the said lever having its lower end pivotally secured, as at 114 to the chute 33, or to a suitable part of the frame 15. 75 The lever works through a slot in a segment 115, the said segment being provided with any desired number of spaced teeth which are engaged either by the edge of the lever 113 or by a pawl carried by the said lever. It will be apparent that when the lever 113 is swung to engage with one of the notches of the segment elements connected with the links the yoke members 80 that support the brushes will be swung or 85 turned upon their pivots to bring the said brushes a desired distance inward or out of the frames therefor and when the lever is brought to other notches the brushes will be further advanced toward or away from 90 their frames. The yieldable connection between the supporting link 99 and the bearing member 102 permits of both the blacking and polishing brushes passing over any 95 irregular surface in the shoe operated on, 100 and it is thought, from the foregoing description, when taken in connection with the drawings, that the details of the construction and the operation thereof will be apparent without further detailed description. 105

Having thus described the invention, what is claimed as new, is:—

1. In a shoe shining machine, pivoted foot rests, coöperating pairs of blacking 110 brushes and polishing brushes at the opposite sides of the respective foot rests, frames carrying said brushes, shafts supporting said frames, and said frames being slidable on said shafts, means for imparting a reciprocal movement to the frames and brushes, liquid polish containing pans below the blacking brushes, feed blocks in said pans supported by the foot rests, means for elevating the foot rests at predetermined 115 intervals to elevate the feed blocks and deliver a quantity of polish to the blacking brushes, means for turning said frames at predetermined intervals to bring the blacking brushes to operative position, and spring 120 means for returning said frames to initial position to arrange the polishing brushes in operative position.

2. In a shoe shining machine, a revoluble element having cams thereon, pivoted foot 125

- rests above said element having depending arms in the path of contact with said cams, liquid blacking containing pans at the opposite sides of the foot rests and above the 5 revoluble element, blocks received in said pans, said blocks having their outer faces convexed and being provided with pockets and openings between said pockets, frames above the pans, a polishing brush and a 10 blacking brush arranged at right angles to each other and supported by said frames, sleeves on the frames, shafts received in said sleeves, means for imparting a reciprocatory movement to the frames and brushes when 15 the revoluble element is in motion, means actuated by the revoluble element for turning the frames on their respective shafts at predetermined intervals whereby to bring the respective pairs of blacking brushes in 20 operative position, spring means for returning the frames to initial position and arranging the polishing brushes in operative position, and the foot rests, when operated by the cams designed to elevate the blocks 25 into contacting engagement with the blacking brushes to supply said brushes with a quantity of blacking.
3. In a shoe shining machine, a revoluble element having cams thereon, pivoted foot 30 rests, depending arms thereon having rollers in the path of travel of the cams, liquid blacking feed blocks supported by the rests, coöperating blacking applying brushes and polishing brushes arranged in pairs at the 35 opposite sides of the rests, and the respective polishing and blacking brushes being disposed angularly with respect to each other, and the said blacking brushes when in inoperative position adapted to be contacted by the blacking feed blocks when the pivoted rests are actuated by the cams on the revoluble element, means for reciprocating the brushes, and means for bringing the polishing brushes into operative position.
4. In a shoe shining machine, a rotary element, means for imparting motion thereto, cams on said element, a cam on the periphery of the said element, pivoted foot 45 rests above the element, roller carrying depending members on said foot rests, the said rollers arranged in the path of travel of the cams, blacking feed means carried by each of the foot rests, polishing brushes and 50 blacking applying brushes disposed at right angles to each other and arranged on the opposite sides of the foot rests, frames for said brushes, a sleeve on each of said frames, a shaft received in each of said sleeves, means for imparting a reciprocatory movement to the frames when the revoluble 55 element is in motion, spring means for retaining the frames in one position whereby to arrange the polishing brushes in operative relation, a pivoted trigger in the path of travel of the cam on the revoluble element, means connected with said trigger and with the sleeves of the frames for further revolving said frames on their shafts against the influence of the spring means to bring the blacking brushes to operative position and the polishing brushes to inoperative position, means for imparting a continuous blast of air between the coöperating brushes when the frames are reciprocated, and the blacking brushes being disposed in 60 the path of contact with the feed means carried by the rests.
5. In a shoe shining machine, a rotary element, a motor for imparting motion thereto, reciprocatory shaft supported frames arranged in spaced pairs, two angularly arranged brushes on each of said frames and the brushes of the adjacent frames designed to coact in polishing and applying blacking to shoes, foot rests between each 65 pair of frames on which the shoes rest when being polished, means carried by the foot rests for feeding a quantity of blacking to the blacking brushes, means for imparting a reciprocatory movement to the brush carrying frames when the rotary element is in motion, means for rotating the frames to alternately bring the blacking and polishing brushes to operative positions, means operated by the rotary element for elevating 70 the foot rests out of contact with the brushes when the frames thereof are turned to bring either the polishing or blacking brushes to operative position, and means carried by the rotatable element and engaging with the motor to stop the same and halt the movement of the rotary element when the 75 said element has been turned a predetermined distance.

In testimony whereof I affix my signature.
VINCENT N. VOGT.
